UNITED STATES PATENT OFFICE.

ROBERT A. GIBSON, OF BERKELEY, AND JOHN B. SARTOLOU, OF EMERYVILLE, CALIFORNIA.

LEAF-TURNER.

1,127,227.

Specification of Letters Patent.

Patented Feb. 2, 1915.

Application filed May 29, 1911. Serial No. 630,012.

To all whom it may concern:

Be it known that we, ROBERT A. GIBSON, residing at Berkeley, Alameda county, California, and JOHN B. SARTOLOU, residing at Emeryville, Alameda county, California, both citizens of the United States, have invented new and useful Improvements in Leaf-Turners, of which the following is a specification.

10 This invention relates to a mechanical leaf-turner for holding and turning music, advertising cards, photographs, etc.

It is the object of this invention to provide a simple, practical, automatic, continuously-operating leaf-turner, which is adapted to be operated by means of an electric motor or other motive power, and which is especially suitable for use in displaying and exhibiting sheet pictorial illustrations, signs 20 and the like, in succession.

Another object is to provide means in a leaf-turner by which the direction of rotation of the leaf turning mechanism will be automatically reversed after a predetermined number of leaves have been turned 25 in one direction, so as to return the leaves successively in the other direction and so on; the series of leaves being turned first one way, then the other, so as to display each 30 leaf a number of times by the continued operation of the machine.

The invention consists of the parts and the construction and combination of parts, as hereinafter more fully described and 35 claimed, having reference to the accompanying drawings, in which—

Figure 1 is a side elevation of the invention. Fig. 2 is a front end view of same. Fig. 3 is an enlarged section on the line 40 X—X, Fig. 1. Fig. 4 is an enlarged section on the line Y—Y, Fig. 1. Fig. 5 is a detail in side elevation of the automatic reversing mechanism. Fig. 6 is a detail in perspective of the trip-lever. Fig. 7 is a detail in vertical section of the traveling leaf actuator.

In the drawings A represents the frame of the machine which is supported on a pedestal B, which frame and pedestal may be of any suitable design or construction.

50 Rigidly mounted on the frame A is a stationary shaft 2, having a portion of its length screw-threaded, as at 3, on which a nut 4 is mounted, as shown in Fig. 7; and surrounding the threaded portion 3 and the nut 55 4 is a cylinder 5 which is revolvably mount-

ed on the stationary shaft 2 and is adapted to be rotated continuously in either direction, as later described, by means of a motor 6 mounted on the frame A, or by any other suitable source of power. The cylinder 5 is 60 slotted longitudinally, as at 7, through which slot a tubular projection 8 on the nut 4 extends; this projection 8 being engaged by the sides of the slot 7 so that the nut 4 will be rotated in synchronism with the cylinder 65 5, as the latter is rotated around the shaft 2.

Slidably mounted in the tubular member 8, on the nut 4, is a bolt 9, the outer end of which normally projects beyond the outer end of the member 8; a spring 10 in the 70 member 8 bearing against the inner end of the bolt to retain it in its outermost position, and a pin 11 extending through the bolt riding in slots in the member 8 being provided to limit its outward movement. 75 Means are provided for drawing the bolt 9 within the member 8 in opposition to the spring 10, which means are here shown as consisting of a cam plate or flange 12 which is adapted to engage the 80 outer end of the pin 11 as the nut 4 and the member 8 are revolved and cause them and the bolt 9 to move backward in the member 8. The cam plate or flange 12 is formed on a sleeve 13 loosely mounted on the cylinder 85 5; the cylinder 5 being free to rotate in the sleeve 13, as later described.

Pivottally mounted on the shaft 2 is a series of sheet holders 14, each of which consists of a pair of parallel clamping plates, 90 between which a card or sheet 15 may be rigidly held; these plates being mounted at each end on an arm which terminates in a sleeve loosely mounted on the shaft 2. The inner edge of the leaf-holders 14 is in parallel relation to the shaft 2, and each holder has a lug or projection 16 formed on its inner edge, which projection is so disposed as to be engaged by the bolt 9 when the latter is in its outermost position. The lugs or 100 projections 16 on the adjacent leaf-holders 14 are arranged in an off-set, or stepped up, fashion in relation to each other, so that when the bolt 9 of the actuator is moved by the action of the screw 3 after engaging 105 the lug or projection 16 on one leaf-holder, the projection 16 on the adjacent leaf-holder will be in line with the bolt 9 in the new position. The plate-holders 14 are supported on either side of the machine by means 110 119

of buffers 17 mounted on parallel rods 18 supported in brackets formed on each side of the frame A, as shown in Figs. 2 and 3.

The mechanism for rotating the cylinder 5 consists of a gear 19 on the cylinder 5 which is adapted to be engaged by either one of a pair of worm-gears 20-20', disposed on opposite sides of the gear 19, which are designed to be alternately thrown in and out of engagement with the gear 19, as will be later described. The worm-gears 20-20' are mounted on vertically disposed shafts 21-21' which have gears 22-22' mounted on their lower ends, and which are supported in a rocking frame 23 pivoted at 24 on the frame A. The gears 22-22' are disposed on opposite sides of a worm-gear 25 mounted on the drive shaft of the motor 6, and are in constant mesh therewith, from which it will be seen that when the motor 6 is in operation the worm-gears 20-20' will be rotated continuously.

Means are provided for rocking the frame 24 at predetermined intervals, so as to alternately throw first one and then the other of the worm-gears 20-20' into engagement with the gear 19 on the cylinder 5. These means consist of a rocking lever 26 mounted on a member of the frame A, which lever has an angularly disposed groove 27 on its inner end which engages a pin 28 on the back of a vertical member on the rocking frame 24 in such manner that when the lever 26 is rocked backward and forward in one direction, the frame 24 will be caused to rock backward and forward in a direction at right angles to that of the movement of the lever 26.

The rocking of the lever 26 is accomplished automatically by means controlled by the movement of the nut 4 on the worm 3, which means includes a pair of connected rocking arms 29-29' arranged to extend on opposite sides of the lever 26 and pivoted at a point some distance therebelow. The upper ends of the arms 29-29' are pivotally attached to connecting rods 30-30' which parallel the rods 18 and are connected therewith by means of blocks 31-31'. The blocks 31-31' are rigidly and adjustably mounted on the connecting rods 30-30' and are slidably mounted on the rods 18; the block 31 on the rod 30 being adapted to be engaged by an arm 32 on the sleeve 13 as the latter is carried upward on the cylinder 5, so as to rock the arm 29 in a forward direction, and the block 31' on the rod 30' being adapted to be engaged by the arm 32 on the sleeve 13 as the latter is carried downward on the cylinder 5, so as to rock the arm 29' in a backward direction.

A helical spring 33 is attached to the frame A and the arm 29' in such manner as to exert a downward pull on the latter so as to accelerate the movement of the arms

29-29' in either direction after the arms have been carried a certain distance by the slow action of the arm 32 on the sleeve 13, and to retain the arms 29-29' in either their forward or rearward positions.

70

Projections 34-34' are formed on the opposite ends of the lever 26, which projections extend on opposite sides of the arm 29' and in the path of movement thereof in such manner that when the arm 29' is rocked in either direction by the quick action of the spring 33, the lever 26 will be caused to quickly rock in a corresponding direction and thereby quickly throw one of the worm-gears 20-20' out of engagement with the gear 19 and the other gear into engagement therewith.

75

A dog or pawl 35, pivoted on the frame A, is provided as a means for retaining the rocking lever 26 in either of its positions; a notch or shoulder 35' engaging a projection 36 on the latch 26 when the rear end of the lever is uppermost, and a shoulder 37 on the forward end of the pawl 35 engaging a lip 38 on the forward end of the lever 26 when the latter is in its uppermost position. The pawl 35 is released from engagement with the lever 26 by means of a pin 39 on the arm 29, which pin travels over a cam surface on the pawl 35 in such manner as to raise the pawl 35 when the arm 29 is traveling on either its forward or backward movement.

85

In the operation of the invention the worm 25 is caused to revolve by setting the motor 6 in motion which rotates the gears 22-22', shafts 21-21' and worm-gears 20-20', as before described. The worm-gear 22 being engaged with the gear 19 on the cylinder 5 causes the latter to revolve on the shaft 2, which movement is transmitted to the nut 4 and the bolt 9 mounted thereon. As the nut 4 is rotated on the threads 3, it is caused to slowly advance upward on the shaft 2 carrying the bolt 9 and the sleeve 13 therewith, with the arm 32 on the sleeve 13 contacting with the underside of the bar 18, as shown in Figs. 1 and 2. As the bolt 9 travels around the shaft 2 with the cylinder 5, it comes in contact with a projection 16 on a leaf-holder 14, so as to cause the leaf-holder to turn around the shaft 2 therewith. The moment the leaf-holder is carried a little beyond a vertical position by the bolt 9, it falls to the opposite side of the shaft 2 where, if it is the first leaf-holder of the series, it will be brought to a stop against the buffers 17; the other leaf-holders of the series being successively stacked thereon by the continued rotation of the actuating bolt 9. The bolt 9, after having turned a leaf-holder, as just described, is retracted into the tubular member 8 by the action of the cam plate 12 on the pin 11, as before described; this action withdrawing the bolt 9

130

clear of the projection 16 on the leaf-holder 14 just actuated. The bolt 9 is now moved up another step by means of the screw 3 and engages the projection 16 on the succeeding 5 leaf-holder 14 and the operation is repeated. As the arm 32 nears the upper end of the shaft 2, it engages the block 31 and moves it along the rod 18, so as to throw the arm 29 over, as before described, to rock the 10 frame C and thus throw the worm-gear 20 out of engagement with the gear 19 and throw the gear 20' into mesh therewith. This reverses the direction of rotation of the cylinder 5 and also changes the direction of 15 movement of the nut 4 on the worm 3, so that the leaf-holders 14, previously turned, will now be returned successively. In reversing the direction of rotation of the cylinder 5 and the actuating bolt 9, the sleeve 20 13 will be turned with the cylinder by reason of the bolt 9 contacting with the opposite end of the cam or flange 12, so that the arm 32 will bear against the bar 18'. As the arm 32 moves downward along the bar 18', 25 it comes in contact with the block 31' and sets the reversing mechanism into operation again, as before described.

From the foregoing it will be seen that the actuating bolt 9 will be caused to travel back and forth on the shaft 2 so as to turn the 30 series of leaf-holders, first to one side, then to the other, and that the leaf-holders will be in a state of rest for the period of time consumed by the bolt 9 in traversing approximately three-quarters of a revolution. This interval of rest gives an observer an 35 opportunity to see the pictures or read the characters displayed on the sheets 15.

Having thus described my invention, what 40 I claim and desire to secure by Letters Patent is—

1. In a leaf-turner, the combination with a series of hinged leaf-holders, of a traveling actuator constructed and arranged to 45 turn said leaf-holders successively, means for giving said actuator a continuous spiral movement first in one direction and then in the other direction, said means consisting of a nut on which said actuator is mounted and 50 a stationary screw-threaded shaft on which the nut is mounted, a slotted cylinder on said stationary shaft, a gear on said cylinder, a continuously rotating worm-gear on each side of said gear, and automatic means 55 by which first one worm-gear and then the other will be thrown in and out of mesh with said gear.

2. In a leaf-turner, the combination with a series of hinged leaf-holders, of a traveling 60 actuator constructed and arranged to turn said leaf-holders successively, means for giving said actuator a continuous spiral movement first in one direction and then in the other direction, said means consisting 65 of a nut on which said actuator is mounted

and a stationary screw-threaded shaft on which the nut is mounted, a slotted cylinder on said stationary shaft, a gear on said cylinder, a continuously rotating worm-gear on each side of said gear, a rocking frame, 70 shafts on which the worm-gears are mounted supported in said frame, and means for rocking said frame at predetermined intervals.

3. In a leaf-turner, the combination with 75 a series of hinged leaf-holders, of a traveling actuator constructed and arranged to turn said leaf-holders successively, means for giving said actuator a continuous spiral movement first in one direction and then in 80 the other direction, said means consisting of a nut on which said actuator is mounted and a stationary screw-threaded shaft on which the nut is mounted, a slotted cylinder on said stationary shaft, a gear on said cylinder 85 shaft, a continuously rotating worm-gear on each side of said gear, a rocking frame, shafts on which the worm-gears are mounted supported in said frame, and means for rocking said frame at predetermined intervals, 90 said frame-rocking means controlled by the movement of said actuator.

4. In a device of the character described having a series of hinged leaf-holders, a traveling actuator adapted to engage said 95 leaf-holders successively, consisting of a stationary threaded shaft, a nut thereon, a tubular projection on said nut, a bolt slidably mounted therein, means for rotating said nut, and means for advancing and retracting 100 said bolt as the nut revolves.

5. In a device of the character described having a series of hinged leaf-holders, a traveling actuator adapted to engage said leaf-holders successively, consisting of a stationary threaded shaft, a nut thereon, a tubular projection on said nut, a bolt slidably mounted therein, means for rotating said nut, and means for advancing and retracting 105 said bolt as the nut revolves, said means consisting of a resilient member in said tubular projection, a pin on said bolt and a cam surface adapted to bear against said pin.

6. In a device of the character described having a series of hinged leaf-holders, an 110 actuator adapted to successively engage said leaf-holders, consisting of a retractable spring-actuated member, a nut on which said member is mounted, a screw-threaded shaft on which said nut is mounted, and 115 means for advancing the nut on the threaded shaft in either direction.

7. In a device of the character described having a series of hinged leaf-holders, an actuator adapted to successively engage said 120 leaf-holders, consisting of a retractable spring-actuated member, a nut on which said member is mounted, a screw-threaded shaft on which said nut is mounted, means for rotating the nut on the threaded shaft in either 125 130

direction, and means for retracting said spring actuated member upon the rotation of the nut.

8. In a leaf-turner, the combination with a series of hinged leaves, of a leaf actuator having a spiral movement, means for giving the actuator said spiral movement, said means including a pair of oppositely acting driving gears, and means for automatically 10 reversing the direction of travel of said actuator, said reversing means including devices for determining which of said driving gears is to be effective.

9. In a leaf-turner, the combination of a 15 series of hinged leaf holders, a traveling actuator, a stationary screw, and mechanism for operating said actuator, said mechanism including a worm-gear, a drive shaft on which said worm-gear is mounted, a pair of 20 gears meshing with said worm-gear, shafts on which said gears are mounted, a worm-gear on each of said shafts, a gear disposed between said last-named worm-gears, and means for throwing first one worm-gear 25 then the other into mesh with said last-named gear for turning said hinged leaf holders first in one direction and then in the other.

10. In a leaf-turner, the combination of 30 a series of hinged leaf holders, a traveling actuator, a stationary screw, and mechanism for operating said actuator, said mechanism including a worm-gear, a drive shaft on which said worm-gear is mounted, a pair of 35 gears meshing with said worm-gear, shafts on which said gears are mounted, a worm-gear on each of said shafts, a gear disposed between said last-named worm-gears, and

Copies of this patent may be obtained for five cents each, by addressing the "Commissioner of Patents, Washington, D. C."

means for throwing first one worm-gear then the other into mesh with said last-named gear for turning said hinged leaf holders first in one direction and then in the other, 40 said means including a rocking frame, a pin on said rocking frame carrying said pair of gears, a lever, a slot in said lever engaging 45 said pin, and means for rocking said lever to actuate the rocking frame.

11. In a leaf-turner, the combination of a series of hinged leaf holders, a traveling actuator, a stationary screw, and mechanism 50 for operating said actuator, said mechanism including a worm-gear, a drive shaft on which said worm-gear is mounted, a pair of gears meshing with said worm-gear, shafts 55 on which said gears are mounted, a worm-gear on each of said shafts, a gear disposed between said last-named worm-gears, and means for throwing first one worm-gear then the other into mesh with said last-named gear for turning said hinged leaf holders 60 first in one direction and then in the other, said means including a rocking frame, a pin on said rocking frame, a lever, a slot in said lever engaging said pin, and means for rocking 65 said lever to actuate the rocking frame, consisting of a rocking arm, a spring to exert a pull on said arm, and means for actuating said arm from a remote point.

In testimony whereof we have hereunto set our hands in the presence of two subscribing witnesses.
